(57) CLAIM

The ornamental design for a football dart board, as shown and described.

DESCRIPTION

FIG. 1 is a perspective view of football dart board showing my new design of the present invention;

FIG. 2 is a front plan view of my football dart board of the present invention;

FIG. 3 is a rear plan view of my football dart board of the present invention; and,

FIG. 4 is a right side view of my football dart board of the present invention.
